[57] CLAIM

The ornamental design for a headlight cover, as shown and described.

DESCRIPTION

FIG. 1 is a front elevational view of a headlight cover embodying our new design;

FIG. 2 is a side elevational view thereof, all sides of the design appearing substantially the same;

FIG. 3 is a cross-sectional view taken along the line 3-3 in FIG. 1;

FIG. 4 is a rear elevational view thereof;

FIG. 5 is a front elevational view of a second embodiment of our new design, the second embodiment differing from the first embodiment only in the lens pattern.

FIG 1**FIG 2****FIG 3****FIG 4****FIG 5**
